(74) *Attorney, Agent, or Firm* — Christensen O'Connor Johnson Kindness PLLC

(57) **CLAIM**
The ornamental designs for a closure, as shown and described.

DESCRIPTION

FIG. 1 is a perspective view of the design of the present application taken from above;
FIG. 2 is a bottom perspective view of the design of FIG. 1;
FIG. 3 is a side elevational view of the design of FIG. 1 taken from the left-hand side of FIG. 1;
FIG. 4 is a top view of the design of FIG. 1;
FIG. 5 is a bottom view of the design of FIG. 1;
FIG. 6 is an end view of the design of FIG. 1 taken from the left-hand end of FIG. 4;
FIG. 7 is an end view of the design of FIG. 1 taken from the opposite end of FIG. 4 than shown in FIG. 6.
FIG. 8 is an perspective view of another embodiment of the present application taken from above with parts shown in broken lines;
FIG. 9 is a bottom perspective view of the design of FIG. 8;
FIG. 10 is a side elevational view of the design of FIG. 8 taken from the left-hand side of FIG. 8;
FIG. 11 is a top view of the design of FIG. 8;
FIG. 12 is a bottom view of the design of FIG. 8;
FIG. 13 is an end view of the design of FIG. 8 taken from the left-hand end of FIG. 11; and,
FIG. 14 is an end view of the design of FIG. 8 taken from the opposite end of FIG. 11 than shown in FIG. 13.
The broken lines in FIGS. 8-14 depict unclaimed environmental subject matter and form no part of the claim.

1 Claim, 4 Drawing Sheets
